MATERIAL-PERFORATING AND EYELET-
SETTING APPARATUSOlaf Stenson, Chicago, Ill., assignor to Western
Electric Company, Incorporated, New York,
N. Y., a corporation of New York

Application November 23, 1944, Serial No. 564,867

2 Claims. (Cl. 218—14)

1

This invention relates to article working apparatus and more particularly to a combined perforating and rivet setting apparatus.

An object of this invention is the provision of a simple and practicable apparatus combining means for efficiently performing perforating and rivet setting operations.

In accordance with the above object, wherein the features of this invention, in one embodiment thereof, are applied to an apparatus for attaching terminals by means of eyelets to long flat resistance cards to be used in potentiometers, there is provided a single supporting frame on which are mounted vertically aligned or superposed perforating and rivet setting heads arranged below and above a common bed. Reciprocably mounted in the frame is a die cooperating with a fixed card perforating punch mounted on the lower face of the common bed and an eyelet setting tool cooperating with a fixed die mounted on the upper face of the common bed. A common actuating means employing a spring-returned toggle mechanism operatively connected to the reciprocable perforating die and rivet setting tool serves to operate the latter die and tool, which are used alternately first to perforate the card and then to set an eyelet passing through the card perforation and a perforated terminal member to seal the terminal member to the card.

Other objects and advantages of this invention will more fully appear from the following detailed description, taken in conjunction with the accompanying drawings, in which

Fig. 1 is an elevation, partly in section, of a perforating and rivet setting apparatus embodying the features of the invention;

Fig. 2 is a front elevation of the apparatus as viewed from the left of Fig. 1;

Figs. 3 and 4 are enlarged fragmentary central vertical sections of portions of Fig. 1 showing the rivet setting tool and die and the perforating punch and die, respectively, in their normal inoperative positions; and

Figs. 5 and 6 are fragmentary vertical sections through the terminal member, card and eyelet before and after the eyelet setting operation.

Referring to the drawings, 10 indicates a vertical frame which may be suitably attached to a work bench or other support, indicated fragmentarily at 11. Reciprocably mounted for vertical movement in upper and lower forwardly extending arms 12 and 13 (Fig. 2) of the frame is an eyelet setting tool 14 and a perforating die 15, respectively. Intermediate the arms 12 and 13 is an arm 18, which serves as a common bed

2

for supporting a fixed punch 19, which cooperates with the perforating die 15 and a fixed die 20, which cooperates with the eyelet setting tool 14. The setting tool 14 and die 20 are so formed that, upon a downward operative movement of the tool 14 (Fig. 3), an eyelet 22 seated on the die 20 and having its tubular portion extending through apertures in a flat resistance card 23 and a terminal member 24 will be set and clinched in the manner shown in Fig. 6.

Recesses 25 and 26 are provided in the upper and lower frame arms 12 and 13, in which are pivoted at 29 and 30 levers 31 and 32, respectively. The lever 31 is suitably pivotally connected at one end at 33 to a bifurcated upper end of the setting tool 14 and the lever 32 is similarly connected at 36 to the die 15, the end of the lever being entered in a slot 37 in the die. At their opposite or right ends (Fig. 1), the levers 31 and 32 are pivotally connected at 38 and 39 to outer ends of toggle links 40 and 41, respectively, the inner ends thereof being pivotally connected at 44. Attached to the toggle link 40 is an L-shaped lever 45, to the lower end of which is fixed, as indicated at 46, one end of a flexible link or cord 47, the cord extending forward, as viewed in Fig. 2, or to the left, as viewed in Fig. 1, and over a guide or pulley wheel 48 journaled on a bearing arm 49 integral with the frame 10. From the pulley wheel 48, the cord 47 extends downwardly and is connected to a suitable foot treadle (not shown).

Slidably fitted in an aperture formed in the frame 10 is a hollow plunger 51, which is normally urged outwardly by a compression spring 52 bearing at opposite ends against inner walls of the aperture and plunger. The outer end of the plunger 51 constantly engages overlapping inner end faces of the toggle links 40 and 41 and in central alignment with the pivotal connection 44. In the normal position of the toggle links 40 and 41 and the plunger 51, as shown in broken outline in Fig. 1, the levers 31 and 32 will also assume the broken outline position thereof, wherefore they bear against inclined stop faces 53 and 54 on the frame 10. In this position of the levers 31 and 32, the rivet setting tool 14 and perforating die 15 are maintained in their retracted positions (Figs. 3 and 4). A coiled tension spring 55 connected at opposite ends to the pivotal connection 38 and a pin 58 fixed in the frame 10 also acts with the spring-pressed plunger 51 to maintain the toggle links in their normal broken outline position. Carried by the lever 31 is an adjustable stop screw 59, engageable with a surface

of the frame 10 to limit the operative movement of the lever and thereby the rivet setting tool 14, as shown to the full line position of these parts in Fig. 1. To limit a similar movement of the lever 32 and thereby the perforating die 15, as shown in full line position in Fig. 1, an adjustable stop screw 60 is mounted in the frame arm 13.

Fulcrumed at its inner or right end (Fig. 1) in a notch 61 formed in the frame 10 is a stripper plate 62, which, at its outer or left end, is slotted at 65 to freely surround the perforating punch 19. A tension spring 66 entered in an aperture in the frame arm 18 and attached at its upper end, as indicated at 67, to the arm and, at its lower end, as indicated at 68, to the stripper plate, serves to normally maintain the plate in its normal position abutting the lower face of the frame arm 18. Journalled in bearing plates 69 fixed to opposite faces of the frame arm 18 and also in the arm is a rotatable shaft 72, which is notched intermediate its ends to provide a flat face 73, which normally bears in parallel relation against the upper face of the stripper plate. A handle 74 attached to one end of the shaft 72 provides means for manually actuating the shaft in a counterclockwise direction (Fig. 1) to cam the stripper plate 62 about its fulcrum point 61 and thus stripping the perforated card 23 from the perforating punch 19.

In the use of the apparatus above described, the flat card 23, with a perforated terminal member 24 correctly located thereon and retained in position by a suitable tool, which includes clamping jaws 75, shown fragmentarily (Figs. 1 and 4), is entered between the retracted perforating die 15 and the fixed punch 19, the perforation in the terminal member being aligned with and pressed upwardly to enter the punch therein, as shown in Fig. 4. While the card 23 and terminal member 24 are held in the position described, the foot treadle (not shown) is depressed and, by means of the cord 47 and lever 45, the toggle links 49 and 41 are actuated from their normal broken outline positions to their operative full line positions (Fig. 1), which serves to simultaneously rock the levers 31 and 32 to their full line positions, thus advancing the perforating die 15 upwardly to cause, in cooperation with the stationary punch 19, a perforation of the card 23. At the same time, the rivet setting tool 14 is idly advanced downwardly. Upon release of the foot treadle, the operative parts of the apparatus are returned in the manner previously described by the action of the spring-pressed plunger 51 and the spring 55 to their broken outline positions. Thereafter, the perforated card 23 is stripped from the punch 19 in the manner described hereinbefore by rocking the hand lever 74 in a counterclockwise direction (Fig. 1).

Without releasing the clamping jaws 75, an eyelet 22 is then pressed by hand into the perforations in the card 23 and terminal member 24 from below (Fig. 5) and then the assembled parts are inserted between the retracted rivet setting tool 14 and the fixed die 20 with the lower end of the eyelet 22 seated in the die 20, as shown in Fig. 3. While the parts 22, 23 and 24 are thus positioned, the foot treadle (not shown) is again depressed and, in the manner previously described, the rivet setting tool 14 is advanced downwardly to set and clinch the eyelet 22 and secure the terminal member 24 to the card 23 and simultaneously therewith the perforating

die 15 is idly advanced upwardly. The release of the foot treadle returns the rivet setting tool 14 and perforating die 15 to their normal positions and the attaching of terminal members 24 to card 23 is repeated in the manner above described by alternate use of the perforating die 15 and cooperating punch 19 and the rivet setting tool 14 and cooperating die 20.

What is claimed is:

1. In a perforating and rivet setting apparatus, a frame, a perforating punch and die set on said frame, a rivet setting tool and die coaxially aligned therewith on said frame, said perforating punch and rivet setting die being fixedly supported on said frame between said perforating die and rivet setting tool, said latter die and tool being reciprocably mounted on said frame, levers operatively connected to said perforating die and rivet setting tool, a toggle mechanism comprising a pair of similar links interconnected at adjacent ends and operatively connected at their opposite ends to said levers, means for actuating said toggle mechanism to simultaneously actuate said perforating die and rivet setting tool, and a spring pressed plunger mounted in said frame operatively bearing against said adjacent ends of said links for returning said toggle mechanism and thereby said perforating die and rivet setting tool to their normal positions.
2. In a perforating and rivet setting apparatus, a frame having an arm extending laterally therefrom, said arm being provided on one surface with a fixed element of a punch and die means and on the opposite surface with an aligned fixed element of a rivet setting means, a pair of oppositely moving aligned plungers mounted in said frame, one of said plungers carrying the other element of said punch and die means and the other plunger carrying the other element of said rivet setting means, levers pivoted on said frame and operatively connected to said plungers, a toggle mechanism comprising a pair of similar links pivoted at their opposite ends to said levers and at their other ends to each other, an actuator fixed to one of said links for operating said toggle mechanism to simultaneously actuate said plungers and thereby said elements of said punch and die means and said rivet setting means, and a spring pressed plunger mounted in said frame operatively bearing against said pivotally connected other ends of said links for returning said toggle mechanism and thereby said plungers to their normal positions.

OLAF STENSON.
